United States Patent Office

Des. 231,555

Patented Apr. 30, 1974

231,555

TOY TRACKWAY

Haruo Suzuki, Urawa, Japan, assignor to Toytown
Corporation, Tokyo, Japan

Filed Nov. 16, 1972, Ser. No. 307,081

Term of patent 14 years

Int. Cl. D21—01

U.S. Cl. D34—15 MM

FIG. 3

FIG. 2

FIG. 1 is a top plan view of the toy trackway, embodying my new design;

FIG. 2 is a front elevational view thereof;

FIG. 3 is a right side elevational view thereof;

FIG. 4 is a rear elevational view thereof; and

FIG. 5 is a left side elevational view thereof.

I claim:

The ornamental design for a toy trackway, as shown.
